PAUL REISS, OF DANZIG (FREE CITY OF), ASSIGNOR TO THE FIRM GUTSCHOW & CO.
G. M. B. H., OF DANZIG.

CALCULATING MACHINE.

Application filed April 18, 1922. Serial No. 555,321.

To all whom it may concern:

Be it known that I, PAUL REISS, a citizen of Germany, residing at Danzig (Free City of), have invented certain new and useful 5 Improvements in Calculating Machines, of which the following is a specification.

This invention has reference to key operated calculating machines for figuring with several rows of numbers, and especially to 10 automatically recording adding and subtracting machines of that type in which the transferring of the several numerical quantities which are set by the keys to the counting 15 and printing means is effected by means of reciprocating rack bars or the like the ratio of movement of which corresponds to the numerical value of the particular key operated.

In accordance with this invention the ratio 20 of movement of the rack bars or the like which operate the numeral members or wheels of the counting mechanism is determined by means of dogs or coupling members adjustably to be connected to said rack 25 bars or the like, in several positions by the operation of the keys, the said dogs or coupling members being adapted to engage with a projection or stop rigidly secured to the frame of the calculating machine and limiting 30 the movement of the said rack bars or the like. The distances of the positions to which the dogs or the like are adjusted on the rack bars or the like from the stationary movement limiting stop referred to in the 35 inoperative position of the rack bars or the like correspond to the numerical values of the keys corresponding to the respective dogs or the like. The said keys are positively connected to the adjustable dogs or 40 coupling members of the rack bars or the like without, however, causing this connection to interfere with the possibility of dis- placing the rack bars or the like.

The reciprocation of the several rack bars 45 or the like is preferably effected from a common sliding member adapted to be reciprocated with unchanging stroke, and which may be coupled to the rack bars or the like by means of the adjustable dogs or the like 50 referred to.

The invention has reference also to improvements in the particular means of connecting the keys to the adjustable dogs, and it also provides for improved means of ar- 55 ranging said dogs, and for improved means

of causing the common sliding or operating member to become engaged with the rack bars or the like.

My invention will be understood from the accompanying drawing showing a calculating machine by way of example as an embodiment of my invention, in which:

Figure 1 is a vertical section through the keyboard portion with adjoining parts, all the parts not absolutely necessary for the 65 understanding of the invention having been removed from the drawing.

Figure 2 is a section on the line II—II of Figure 1.

Figure 3 is a partial elevation of the parts 70 of machinery illustrated in Figure 1, seen from the opposite side (in the direction of the arrow of Figure 1).

Figure 4 is a horizontal section on the line 75 IV—IV of Figure 1.

Referring particularly to Figure 1 of the drawing a row or column of keys of the key board of the calculating machine are indicated at 1 to 9 and 0. The said keys are arranged as usual in rows or columns one 80 behind the other transversely to the direction in which the numbers for which the machine is to be set will have to be read. Of such numbering rows the machine possesses as many will correspond to the amount 85 of characters for which the machine is intended. In the drawing for the sake of simplifying the explanation of the parts of machinery only one such row of keys has been represented with the adjacent operating mechanism, the drawing illustrating by 90 way of example the keys at the extreme left of the machine. The several keys correspond to the numerical characters by which they are designated in the drawing. Each 95 separate key is provided with a stem 21 constituted by a flat bar, and guided in slots 31 of a flange 33 at the upper end of a sheet metal wall 32 provided for each row of keys, the stems being also guided by lugs 34 obtained by the punching out of parts of the 100 wall 32, and bending the cut-out portions inwards. Springs 35 attached with their upper ends to the flange 33 and with their lower ends to pins 36 of the key stems 21 105 keep the keys in the raised position. Below the pins 36 another pin 37 is secured to each of the stems 21 adapted to engage behind a locking tooth or shoulder 38. The said shoulders 38 of all the keys are provided on 110

a common locking bar 39 guided by means of slots 40 and pins 44 provided in the wall 32 and longitudinally displaceable. The locking bar 39 is drawn to the left of the drawing (Figure 1) by a spring 41 one end of which being attached to the wall 32, while the other end of the spring acts upon the locking bar 39. The top parts of the locking teeth or shoulders 38 are slanted off, so as to cause the respective pin 37 upon the depression of the corresponding key to laterally displace the locking tooth and consequently the bar 39 itself. The zero key is not provided with a locking tooth, but instead of that the bar 39 is provided at the particular point with an inclined face 42 corresponding to the inclined top surface of the teeth 37.

Below each partition wall 32 a rack bar 61 is arranged the teeth 62 of which engage in the well known manner with the teeth of a pinion secured in the numeral wheel 116 of the counting mechanism of the machine. In the case of self-recording calculating machines with printing mechanism the operating means for the printing mechanism may be connected at this point. The rack bars 61 are guided in the slots 64 (Fig. 2) of two indented plates 68 arranged in transverse relation thereto. The rack bars 62 are also supported on rollers 67. Three groups of slots *a* are provided in the rack bars 62, the said groups being distributed along the respective longitudinal row of keys. Each of the slots corresponds to one of the nine keys. In order to assist in the determination of the particular key corresponding to each of the slots the reference characters *a* for the slots have been provided with the corresponding index marks 1 to 9 in the drawing. The position of the rack bar illustrated in Figure 1 corresponds to its position of rest, that is to say to the position in which the zero will appear in the window of the corresponding number wheel; this position will be referred to hereinafter as the "zero-position." In the bottom edge of the sheet metal wall 32 opposite to the upper side of the rack bar 61 nine notches or recesses *b* are provided which register exactly with the slots *a* in the zero position of the rack bar. The lower edge of the sheet metal partition 32 is situated directly above the upper edge of the rack bar 61. The recesses *b* which are provided in the drawing with index marks corresponding to the slots *a* to indicate the keys corresponding thereto, are engaged laterally by dogs or coupling pins *c* (Figure 2) provided upon the lower ends of oscillatable or rocking arms *d* the upper ends of which are pivoted at *e* to horizontal arms *f* rigidly connected to the key stems 21. This kind of connection, however, applies only to the rocking or oscillatable arms corresponding

to the keys 1, 3, 4, 6, 7 and 9 while the rocking arms corresponding to the keys 2, 5 and 8 are pivoted to the stems of the keys 2, 5 and 8 by means of brackets *g*², *g*⁵ and *g*⁸ respectively (Figs. 3 and 4). The rigidly secured arms *f* of the keys 1, 4 and 7 and, on the other hand, the rigid arms *f* of the keys 3, 6 and 9 are alternatingly arranged in different directions, and they are of such length that the particular pivoting points *e*¹, *e*³, *e*⁴, *e*⁶, *e*⁷, *e*⁹ are in substantial alignment with the pivoting points *e*², *e*⁵, *e*⁸. The rigid arms *f* belonging to the keys 1, 3, 4, 6, 7 and 9 extend through recesses or slots 70 of the wall 32, and project upon the other side of the wall 32 opposite the key stems 21, where they are bent toward the central key stem. Other recesses or slots 71 in the wall 32 permit the passage of the brackets *g* carrying the rocking bars *d*², *d*⁵ and *d*⁸, corresponding to the keys 2, 5 and 8 respectively (compare Figure 4). The manner of connecting the dogs or pins *c* to the corresponding key stems is illustrated in Figure 3, it being assumed that the three keys 7, 8 and 9 have been depressed to different degrees. As appears from Figure 1, the key 7 is in connection with the pin *c*⁷ which is lodged in the recess *b*⁷ at the extreme right of the group, while the pin *c*⁸ in the central recess *b*⁸ is connected to the key 8, and the pin *c*⁹ in the recess at the extreme left of the group is connected to the key 9. The position of the groups of slots *a* in the two extreme positions of the rack bar 61 is substantially symmetric relatively to an imaginary vertical line to be drawn through the pivoting axis common to the three rocking arms of the respective group.

The distance of the several slots *a* of each group from each other in the form of construction herein shown in which the counting or numeral wheels 116 have a number of numbering characters equal to the number of teeth of the gear wheels 63, corresponds to the pitch of these toothed gear wheels or to the pitch of the rack bar 61. In the case of counting wheels with repetitions of rows of numbering characters, or in the case of the insertion of motion—transmitting gearing intermediate the rack bar and the counting wheel the distance referred to is a true fraction or a full multiple of the pitch.

Upon the lower edge of the sheet metal wall 32 three stops 15^a, 15^b and 15^c are provided serving for the purpose of limiting the movements of the rack bar towards the right. These movements of the rack bar are effected by means of a slide member or a carriage 111 mounted in lateral guides 112 of the frame 113 of the machine below the rack bars. The said slide member or carriage is operated by means of a pitman rod 114 from a crank 115 which is mounted upon

the driving shaft 161 of the calculating machine, and which may either be operated manually or by means of a suitable motor. Upon the carriage 111 brackets 110 the number 5 of which corresponds to the number of the longitudinal rows of keys are provided and each of which possesses three projections or catches 18^a, 18^b, 18^c which project between the rack bars 61 (Figure 2).

10 The operation of the device is as follows:—

By depressing one of the keys, the key 9 for instance, against the action of the spring 35 the key remains in the depressed position, after the locking tooth 38 has been forced sideways by the pin 37, the locking tooth having again become engaged behind the pin 37 by the operation of the tension spring 41 acting upon the locking bar 39.

15 Upon the depression of the key 9 the corresponding coupling pin or stop c^o is positively moved by the actuation of the key. The said pin becomes disengaged from its recess or notch b^o, and enters the opposite slot a^o to such an extent as to become situated in the path of movement of the catch 18^c. Thus, this catch 18^c upon the next movement of the carriage or slide member 111 which is caused by the rotation of the 20 crank in the direction of the arrow, is adapted to become engaged with the coupling pin c^o. By this means the carriage 111 is coupled to the rack bar 61, resulting in the rack bar being moved to the right 25 until the pin c^o abuts against the rigid stop 15^c. This extreme position of the rack bar 61 corresponds to the right hand dead center position of the crank 115. During this movement the rack bar 61 will have rotated 30 the counting wheel 116 through a distance corresponding to the numerical value of the key that has been depressed, that is to say, in the particular case under consideration, through nine points as an instance. In order 35 to produce this result the distance of the coupling pin c^o in the zero position of the rack bar 61 from the stationary stop 15^c should correspond to nine multiples of the pitch of the rack bar 61, while the distance 40 between the catch 18^c in the left hand dead-center position of the crank from the coupling pin c^o in the zero position of the rack bar 61 should correspond to the single pitch value. As a general rule, the distance of the 45 particular adjustable dog or pin c which is set in its position relatively to the rack bar by the depression of one of the keys from the corresponding stationary stop 15^a, 15^b and 15^c respectively should be equal to a 50 multiple of the pitch of the gearing corresponding to the numbering character of the respective key, while, on the other hand, the distance of the lugs or catches 18^a, 18^b and 18^c respectively from the dogs c in their 55 adjusted positions should correspond to a mul-

tiple of the pitch in accordance with the complement of the respective numbering character.

Upon continuing the rotation of the crank 115 the carriage 111 is returned while the 70 rack bar 61 for the time being remains in its extreme position, until it is again withdrawn by the lug or catch 18^b which, during the return movement, engages with a pin 16 laterally projecting from the rack 75 bar. Upon reaching the zero position in which the slots a register again with the recesses b the locking bar 39 may be released by means of a suitable mechanism not shown in the drawing so that the previously depressed key 9 is free to return to its inoperative position. During this return movement the key carries the coupling pin c^o with it causing it to become disengaged from the slot a^o and to enter the opposite recess b^o. The machine will then be again restored to its normal position ready for operation. In a similar manner the stop pins corresponding to the other keys are operated.

It is not absolutely necessary for the rack bars to be positively operated by means of the catches 18 through the medium of the carriage 111; in the practise of my invention I may also proceed to cause the movement of the rack bars by the carriage by 90 means of yielding connecting members which may comprise for instance springs, sliding clutches or the like. In such cases the stroke of the carriage should preferably be larger than the distance between the two extreme 95 positions of the rack bars, while in the case of the form of embodiment herein shown and described the stroke of the carriage is substantially equal to the distance referred 100 to.

The division of the slots in several groups may, of course, be different from the one herein shown, but the division in three groups is preferable in view of the keys being arranged in sets of nine. Under certain conditions the division in several groups may be entirely dispensed with, and in such case the slots would be arranged in direct succession. Such a form of construction, however, is less recommendable, because in 110 this case the rocking arms d which connect the stems 21 of the keys to the coupling pins c would have to cross each other at frequent points and would be compelled to project excessively and consequently must be extremely long. Furthermore than that, the angular movements imparted to the rocking arms upon the displacement of the rack bar from one extreme position into the other, would become considerably larger than here- 115 tofore shown.

I claim:—

1. In a calculating machine the combination of a counting mechanism, a slidable rack operatively connected to said mech- 120

anism, a stationary stop adapted to limit the movement of said rack in one direction, 5 depressible keys, coupling members operatively connected to said keys and engageable with said rack at different points, and means for moving said rack in the one and in the other direction.

2. In a calculating machine the combination of a counting mechanism, a slidable 10 rack operatively connected to said mechanism and movable from a zero position to different end positions, a stationary stop limiting the movement of said rack in one direction, deppressible keys, adjustable coupling members positively connected to said keys and engageable with said rack at points which in the zero position of said rack are spaced from the stationary stop in accordance with the numerical value of said keys, and means for moving said rack in 20 the one and in the other direction.

3. In a calculating machine the combination of a counting mechanism, a slidable 25 rack operatively connected to said mechanism and movable from a zero position to different end positions, a stationary stop limiting the movement of said rack in one direction, deppressible keys, rocking arms pivotally connected to said keys, coupling 30 pins secured to the lower ends of said arms, said rack having a plurality of slots engageable with said pins so as to couple them to said rack, the distances between said slots in the zero position of the rack and said stop being proportional to the numerical value of the keys, and means for moving said rack in the one and in the other direction.

4. In a calculating machine the combination 40 of a counting mechanism, a slidable rack operatively connected to said mechanism, a stationary stop limiting the movement of said rack in one direction, deppressible keys, coupling members operatively connected to said keys and engageable with said rack at different points, a slide member, a catch engageable with said coupling means, and means to reciprocate said slide member.

5. In a calculating machine the combination 50 of a counting mechanism, a slidable rack operatively connected to said mechanism and movable from a zero position to different end positions, a stationary stop limiting the movement of said rack in one direction, deppressible keys, adjustable coupling members operatively connected to said keys and engageable with said rack at points which in the zero position of said rack are spaced from the stationary stop in accordance with the numerical value of said keys, a slide member, a catch engageable with said coupling means, the distance between the working face of said catch in the one end position of said slide member and the points

of said rack where coupling of said coupling member takes place being proportional to the complements of the numerical values of the respective keys; and means to reciprocate said slide member.

6. In a calculating machine the combination 70 of a counting mechanism, a slidable rack operatively connected to said mechanism, a plurality of stationary stops spaced apart from each other and each of said stops engageable with said rack upon movement thereof in one direction, deppressible keys, a plurality of groups of slots provided in said rack, said groups being spaced apart from each other, the number of said groups corresponding to the number of said stops, the distances of said slots in the zero position of said rack from their respective stops being proportional to the numerical value of the respective keys, adjustable coupling members connected to said keys and engageable with said slots; and means for moving said rack in the one and in the other direction.

7. In a calculating machine the combination 90 of a counting mechanism, a slidable rack operatively connected to said mechanism and movable from a zero position to different end positions, three separately arranged stationary stops, each of said stops engageable with said rack upon movement thereof in one direction, deppressible keys, three groups of slots provided in said rack spaced apart from each other, the distances of said slots in the zero position of said rack from their respective stops being proportional to the numerical value of the respective keys, rocking arms pivotally connected to said keys, coupling pins rigidly secured to the lower ends of said arms, three groups of notches engageable with said pins in their normal position, said notches being in alinement with said slots in the zero position of said rack, a slide member, three catches on said member, respectively engageable with one of said pins on being engaged by its respective slot, and means to reciprocate said slide member.

8. In a calculating machine the combination 115 of a counting mechanism, a slidable rack operatively connected to said mechanism and movable from a zero position to different end positions, three separately arranged stationary stops, each of said stops engageable with said rack upon movement thereof in one direction, deppressible keys, three groups of slots provided in said rack spaced apart from each other, the distances of said slots in the zero position of said rack from their respective stops being proportional to the numerical value of the respective keys, rocking arms pivotally connected to said keys, coupling pins rigidly secured to the lower ends of said arms, three groups of notches engageable with said pins 120 125 130

in their normal position, said notches being in alinement with said slots in the zero position of said rack, a slide member, three catches on said member respectively engageable with one of said pins, on being engaged by its respective slot, rigid arms extending from the outer keys of a group of keys towards the central key of the group, pivotal connection of said rigid arms with certain of said rocking arms, the pivots of the rocking arms of said outer keys being provided at the inner ends of said rigid arms and being in their normal position substantially in axial alinement with the pivot of the rocking arm of said central key, and means to reciprocate said slide member.

9. In a calculating machine the combination of a counting mechanism, a slidable rack operatively connected to said mechanism and movable from a zero position to different end positions, three separately arranged stationary stops, each of said stops engageable with said rack upon movement thereof in one direction, depressible keys, three groups of slots provided in said rack spaced apart from each other, the distances of said slots in the zero position of said rack from their respective stops being proportional to the numerical value of the respective keys, rocking arms pivotally connected to said keys, coupling pins rigidly secured to the lower ends of said arms, three groups of notches engageable with said pins in their normal position, said notches being in alinement with said slots in the zero position of said rack, a slide member, three catches on said member respectively engageable with one of said pins on being engaged by its respective slot, rigid arms extending from the outer keys of a group of keys towards the central key of the group, pivotal connection of said rigid arms with certain of said rocking arms, the pivots of the rocking arms of said outer keys being provided at the inner ends of said rigid arms and being in their normal position substantially in axial alinement with the pivot of the rocking arm of said central key, a partition wall, a notched bottom section in said partition wall, guiding means on said partition wall and engageable with said keys, and means to reciprocate said slide member.

10. In a calculating machine the combination of a counting mechanism, a slidable rack operatively connected to said mechanism and movable from a zero position to different end positions, a stationary stop limiting the movement of said rack in one direction, depressible keys, rocking arms pivotally connected to said keys, coupling pins secured to the lower ends of said arms, said rack having a plurality of slots engageable with said pins so as to couple them to said rack, the distances between said slots in the zero position of the rack and said stop being proportional to the numerical value of the keys, springs in operative engagement with said keys and retaining said coupling pins in their normal position, and means for moving said rack in the one and in the other direction.

11. In a calculating machine the combination of a counting mechanism, a slidable rack operatively connected to said mechanism and movable from a zero position to different end positions, three separately arranged stationary stops, each of said stops engageable with said rack upon movement thereof in one direction, depressible keys, three groups of slots provided in said rack spaced apart from each other, the distances of said slots in the zero position of said rack from their respective stops being proportional to the numerical value of the respective keys, rocking arms pivotally connected to said keys, coupling pins rigidly secured to the lower ends of said arms, three groups of notches engageable with said pins in their normal position, said notches being in alinement with said slots in the zero position of said rack, a slide member, three catches on said member, respectively engageable with one of said pins on being engaged by its respective slot, an abutment on said rack engageable with one of said catches upon the return movement of the rack, and means to reciprocate said slide member.

In testimony whereof I affix my signature in presence of two witnesses.

PAUL REISS.
